UNITED STATES PATENT OFFICE.

WALTER SCHWERDTFEEGER, OF UNTERTURKHEIM, GERMANY, ASSIGNOR TO DAIMLER-MOTOREN-GESELLSCHAFT, OF UNTERTURKHEIM, GERMANY.

DEVICE FOR INDICATING THE OIL CIRCULATION AND OIL PRESSURE.

Application filed September 10, 1921. Serial No. 499,853.

To all whom it may concern:

Be it known that I, WALTER SCHWERDTFEEGER, a subject of the State of Wurttemberg, Germany, residing at Unterturkheim, 5 Wurttemberg, Germany, 2 Hangstrasse, have invented certain new and useful Improvements in a Device for Indicating the Oil Circulation and Oil Pressure, of which the following is a specification.

10 It is known to provide machines and engines, for instance the motors of motor cars, flying machines, and the like, the working parts of which receive the lubricant through the medium of a circulation conduit, with 15 two indicators, one of which makes visible the circulation proper, whereas the other shows the pressure under which the oil circulates.

The present invention relates in general 20 to a device combining the two indicators, and in particular to the special construction of this device, as fully described hereinafter. In order to make my invention more clear, I refer to the accompanying drawings, in 25 which Figure 1 is a front view of one form of construction of the combined indicators, the cover of the device and the dial being removed; Figure 2 is a horizontal section through the device shown in Fig. 1; Figure 3 is an illustration similar to Figure 1 30 but showing a modified form of construction; and Figure 4 is a horizontal section through said modified construction.

Referring to Figures 1 and 2, the casing 1 35 has circular piston guide channels 2 and 3 enclosing correspondingly curved pistons 4 and 5 each respectively subject to the pressure of springs 6 and 7. The space at the end of each piston opposite to the springs 40 communicates with the oil supply conduit, and the pressure of the oil counteracts, thus, the pressure of said springs. Each piston has a conical transverse bore into which extends an arm 8, or 9 respectively, affixed to 45 a spindle 10, or 11 respectively. The spindles extend from the rear to the front, viz, through the front plate of the casing, as well as through the dial 12, and are provided with hands 13 and 14 co-operating with said 50 dial. The rear ends of the spindles 10 and 11 where the arms 8 and 9 are attached have a larger diameter and are formed with conical necks 15 and 16 which are pressed by

55 springs 17 and 18 into correspondingly shaped cavities provided in the central main plate of the casing. Between this plate and the dial conical protective disks are affixed to the spindles 10 and 11; they prevent the oil flowing along the spindles and from obtaining access to the dial.

60 The manner of operation of this device is as follows: The circulating oil enters through the passage 21 into the space at the upper end of the piston 4 which has a lug 4^a preventing the piston from closing said 65 passage. The oil which is under pressure displaces the piston 4 and compresses the spring 6 accordingly. The guide-channel wherein the piston 4 is displaced communicates with the central space 24 of the casing 70 by a passage 22 which is opened when the piston 4 has been sufficiently displaced. Then the oil flows from said guide channel into the space 24. Owing to the displacement of the piston 4, the arm 8 is turned, 75 as is, consequently, also the hand 13. The extent of the displacement depends, of course, upon the pressure of the oil and thus also upon the amount of oil fed into the space at the upper end of the piston 4. If so 80 the quantity of the oil fed changes, the position of the piston 4 and of the hand 13 also changes, the latter then indicating the change that has taken place.

85 The space at the upper end of the piston 5 also communicates with the central space of the casing through an aperture 25 through which the oil enters from said central space into said other space, whereby the piston 5 is correspondingly displaced and the hand 90 14 turned. The piston 5 has a lug 5^a corresponding to the lug 4^a of the piston 4 and preventing the piston 5 from closing the aperture 25. The hand 13 indicates the circulation as such; the hand 14 indicates the 95 pressure, under which the circulation proceeds. The oil leaves the central space 24 through a branch 27. The space containing the spring 7 does not communicate with the central space, but is connected by an aperture 100 26 either with the atmosphere or with a space where the pressure is below that of the atmosphere.

Referring now to Figures 3 and 4, the casing 28 is provided with two parallel cylinders 29 and 30 containing pistons 31 and

32. Each piston is coupled with one arm 33, or 34 respectively, of double-armed levers affixed to the spindles 35 and 36 of the hands 40 and 41. The other arm of each 5 of said levers is subjected to the pull of a spring 43, or 44 respectively. Each spindle has a conical central part 37, or 38 respectively, which is subjected to the pressure of a spring 39; the co-operation of these parts 10 is just like that of the parts 15 and 17, or 16 and 18 respectively, of Figure 2. The manner of operation of this form of construction of the device is as follows:

The oil passes through the conduit 45 15 into the cylinder 29, displaces the piston 31 to the left, and opens finally the outlet 46 through which it finds access into the central space 47. If the amount of the oil fed changes, the sectional area of the outlet 20 46 also changes which change is indicated by the hand 41 upon the corresponding portion of the dial. From the central space 47 the oil enters into the cylinder 30 and displaces the piston 32 to the left, whereby the hand 25 40 is turned. The space 48 communicates through an aperture 49 either with the atmosphere or with a space where the pressure is below that of the atmosphere. The springs 43 and 44 respond to every change 30 of the pressure and move the pistons and the hands back to the right. The oil leaves the central space 47 through the branch 50.

To prevent the oil from reaching the dial, the spindles of the hands are in this instance 35 also provided with conical disks 51 and 52.

Having thus particularly described the nature of my invention, what I claim as new and desire to secure by Letters Patent of the United States is:

40. 1. A device for indicating the oil circulation and oil pressure in the lubricating conduits of machines and engines, comprising, in combination, two pistons; cylinders containing said pistons; a casing containing said cylinders; a connection between the oil supply and one of the cylinders; a connection between the same cylinder and the space within said casing; a connection between this space and the other cylinder; a connection 45 between said casing space and the lubricating conduit; and means for indicating the oil circulation and the oil pressure, as set forth.

55. 2. A device for indicating the oil circulation and oil pressure in the lubricating conduits of machines and engines, comprising, in combination, two pistons; cylinders containing said pistons; a casing containing said cylinders and a casing space; springs 50 so arranged in said casing as to be adapted to displace said pistons, contrarily to the piston movement due to the pressure of the oil; a connection between the oil supply and one of the cylinders; a connection between 60 the said cylinder and the space within the

casing; a connection between this space and the other cylinder; a connection between said casing space and the lubricating conduit; and means for indicating the oil circulation and the oil pressure, as set forth. 70

3. A device for indicating the oil circulation and oil pressure in the lubricating conduits of machines and engines, comprising, in combination, two parallel cylinders; pistons in said cylinders; a dial; two hands adapted to co-operate with said dial; means for transmitting the motions of the said pistons to said hands; a casing containing the said cylinders and having a space communicating with both cylinders, as well as with the lubricating conduit of the respective machine or engine; and a connection between the oil feed conduit and said space. 75 80

4. A device for indicating the oil circulation and oil pressure in the lubricating conduits of machines and engines, comprising, in combination, two parallel cylinders; pistons in said cylinders; a dial; two hands adapted to co-operate with said dial; a common casing for the before mentioned parts; 85 springs so arranged in said casing and associated with the said pistons as to be adapted to be placed under tension by the motions of the pistons and capable of displacing said pistons in the reverse direction proportionately to any decrease in the force exerted by the oil; said casing having a space communicating with the two cylinders and with the lubricating conduit of the respective engine or machine; a connection 90 between the oil supply conduit and one of the said cylinders; and a connection between the other cylinder and a space wherein the pressure is below that of the oil, substantially as described. 95 100

5. A device for indicating the oil circulation and oil pressure in the lubricating conduits of machines and engines, comprising, in combination, two pistons; cylinders containing said pistons; a casing containing said cylinders; a connection between the oil supply and one of the cylinders; a connection between the same cylinder and the space within the casing; a connection between this space and the other cylinder; a connection 110 between said casing space and the lubricating conduit; a dial; two hands adapted to cooperate with said dial; spindles to which the said hands are affixed; protective disks attached to said spindles means for transmitting the motions of the said pistons to the said spindles; and springs so arranged as to be adapted to displace the pistons proportionately to any decrease in the force exerted by the oil, substantially as and for the purpose set forth. 115 120

6. A device for indicating the oil circulation and oil pressure in the lubricating conduits of machines and engines, comprising, in combination, means for indicating the ex- 125 130

tent of oil circulation; adjacent means for indicating the oil pressure; a common casing for both said means, and a passage for conducting the oil within said casing from the first-mentioned means to the said other means.

7. A device for indicating the oil circulation and oil pressure in the lubricating conduits of machines and engines, comprising an indicator to show the extent of oil circulation, a separate indicator to show the oil pressure, instrumentalities controlling each of said indicators, a common casing for both said indicators, and connections for

conducting the oil to the instrumentalities which control both said indicators.

8. A device for indicating the oil circulation and oil pressure in the lubricating conduits of machines and engines, comprising a casing, two cylinders in said casing, a piston in each of said cylinders, means controlled by one of said pistons for indicating the oil circulation, means controlled by the other piston for indicating the oil pressure, and connections for conducting the oil first to one and then to the other of said cylinders.

WALTER SCHWERDTFEGER.
